UNITED STATES PATENT OFFICE.

HARRY H. NOLEN, OF SAN DIEGO, CALIFORNIA.

ENGINE-COMPRESSION-BRAKE APPARATUS.

Application filed August 26, 1924. Serial No. 734,215.

To all whom it may concern:

Be it known that I, HARRY H. NOLEN, a citizen of the United States, residing at San Diego, in the county of San Diego and State of California, have invented a certain new and useful Engine-Compression-Brake Apparatus, of which the following is a specification.

My invention relates to engine-compression brake apparatus for vehicles, and the objects of my invention are: First, to provide such an apparatus whereby the exhaust gases from the engine of the vehicle may be variously retarded in their flow when being discharged into the atmosphere, thus preventing the free revolution of the engine crank-shaft when using the engine as a braking means; second, to provide a valve, having a large inlet opening communicating with the atmosphere, in connection with the intake manifold of the engine, whereby a surplus amount of air is mixed with the fuel gases, thus reducing the vaporized fuel to a non-combustible fluid and thus preventing back-fire or an explosion in the exhaust pipe when using the engine as a brake means when coasting; third, to provide a valve means in the exhaust pipe or exhaust side of the engine to prevent free discharge of the exhaust gases from the engine during the exhaust stroke of the various pistons thereof, thus materially increasing the compression and therefore the braking power when using the engine-compression as a brake means; fourth, to provide an apparatus of this class whereby the auxiliary air valve in connection with the intake manifold or intake side of the engine is opened before the valve means in the exhaust pipe or exhaust side of the engine is closed, thus reducing the vaporized fuel to a non-combustible fluid before the exhaust pipe is closed; fifth, to provide a novelly constructed and arranged apparatus of this class, and sixth, to provide such an apparatus which is very simple and economical of construction, durable, easy to install and operate, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the

accompanying drawings and to the characters of reference thereon, which form a part of this application, in which:

Figure 1 is a fragmentary plan view of an automobile chassis, showing my engine-compression brake apparatus in connection therewith; Fig. 2 is an enlarged side elevational view of the foot pedal for operating my apparatus, with the view taken at 2-2 of Fig. 1; Fig. 3 is a transverse sectional view of the operating rod and one of its supports, showing the means for limiting the movement of the rod and foot pedal, with the section taken at 3-3 of Fig. 1; Fig. 4 is another transverse sectional view, taken 60 through 4-4 of Fig. 1, showing the pivotal connection of the secondary exhaust valve operating arm with the operating rod, and Fig. 5 is an enlarged side elevational view of the exhaust valve in connection with the exhaust pipe and the arm for operating the same, showing the exhaust pipe and operating arm fragmentarily.

Like characters of reference refer to similar parts and portions throughout the several views of the drawings.

The engine 1, intake manifold 2, exhaust pipe 3, air valve 4, air valve operating arm 5, link 6, foot pedal 7, operating rod 8, vehicle frame 9, operating rod supporting bracket 10, stop pin 11, arm 12, tension spring 13, pin 14, secondary exhaust valve operating arm 15, connecting link 16, exhaust valve operating arm 17, exhaust valve 18, and the tension spring 19, constitute the 65 principal parts and portions of my engine-compression brake apparatus.

In the one form of construction of the apparatus embodying my invention I have provided an air valve 4 in connection with and 70 communicating with the interior of the intake manifold 2 of the gas engine 1. This valve 4 is provided with a large opening which, when open, permits additional air in variable quantities to enter the intake 75 manifold and mix with the vaporized fuel permitted to pass into the same from the carburetor. The mixing of the fuel gas passing through the carburetor, when the same is throttled down, with an additional and large 80 amount of air substantially reduces the fuel gas to an inert mixture, thus preventing the explosion of the gases within the engine cylinders as well as in the exhaust line. This valve 4 is preferably a butterfly valve and is 85

provided with a pivotally mounted butterfly valve member 4^a. On one end of the rod pivotally supporting the valve member 4^a is provided an arm 5, the end of which is pivotally connected by means of a ball and socket joint with a connecting link 6, the other end of which link 6 is pivotally connected by means of a ball and socket joint with the outer end of the arm portion of the foot pedal 7, as shown best in Figs. 1 and 2. The hub portion of the foot pedal 7 is secured to the operating rod 8 which is rotatably supported at one end by the vehicle frame 9. Near the other end of the rod 8 is provided a bracket 10, which rotatably supports said rod at said end on a cross member of the vehicle frame. Said bracket is provided on one side with a longitudinally extending lug 10^a, which is adapted to be engaged by the pin 11 secured to the rod 8 when the foot pedal 7 is in a backward or non-brake-applying position. Said rod is provided, preferably intermediate its ends, with a transversely extending arm 12, to the outer end of which is secured the one end of a tension spring 13, the other end of which spring is secured to a stationary portion of the vehicle. Said spring is adapted to normally hold the pin 11 against the lug of the bracket 10, and is, therefore, adapted to hold the foot pedal in a non-brake-applying position.

At the one extended end of the operating rod 8 is pivotally mounted an arm 15 which is pivotally connected at its outer end, by means of a connecting link 16, with the extended end of an arm 17 secured to the extended end of the valve member supporting rod 18^b of the valve 18, the link 16 being connected with the ends of the arms 15 and 17 by means of ball and socket joints.

Intermediate the ends of the exhaust pipe 3 of the engine 1 is positioned the exhaust shut-off valve 18 which is preferably a butterfly valve and is provided with a butterfly valve member 18^a pivotally mounted therein and supported on a rod 18^b extending through the valve casing. On the outside of the casing of the valve 18 is provided a lug 18^c which is adapted to be engaged by a pin 18^d secured to the valve member supporting rod 18^b. Near the extended end of the arm 15 is secured the one end of a tension spring 19, which is connected at its other end with the stationary portion of the vehicle and is adapted to hold the pin 18^d against the lug 18^c of the valve, and is, therefore, adapted to hold the butterfly valve in an open position.

On the one side of the hub portion of the arm 15 is provided an arcuately cutaway portion 15^a through which the pin 14, secured to the rod 8, extends. This arcuately cutaway portion of the arm 15 permits the rod 8 to be rotated a slight distance before the arm 15 is rotated against the tension of a

spring 19, and, therefore, permits the valve 4 to be opened a short time before the valve 18 is closed or partially closed.

Thus, it will be seen that when the valve 4 is opened before the valve 18 is closed the fuel will be sufficiently mixed with air as to form a non-combustible fluid, thereby preventing backfire and possibility of blowing out the valve member of the valve 18, the exhaust pipe or other parts of the engine. 75

It is obvious from this construction, as illustrated in the drawings and disclosed in the foregoing specification, that there is provided an engine-compression brake apparatus as aimed at and set forth in the objects of the invention, and though I have shown and described a particular construction, combination and arrangement of parts and portions, I do not wish to be limited to this particular construction, combination and arrangement, but desire to include in the scope of my invention the construction, combination and arrangement substantially as set forth in the appended claims. 80

Having thus described my invention, what I claim as new and desire to secure by Letters Patent, is:

1. In an engine-compression brake apparatus for vehicles, an air intake valve in connection with the intake means of the engine of said vehicle for admitting air to said intake means, said air intake valve being disconnected and operable independently from the conventional throttle valve of the engine, an exhaust shut-off valve positioned in the exhaust line of said engine, and means in connection with said valve for slightly opening said air intake valve prior to the closing action of said shut-off valve. 95

2. In an apparatus of the class described, the combination with an internal combustion engine, of a shut-off valve means positioned in the exhaust line of said engine, an air valve in connection with the intake means of said engine for admitting air thereto, and unitary means connected with said shut-off valve means and said air valve for simultaneously opening said air valve and closing said shut-off valve. 100

3. In an apparatus of the class described, the combination with an internal combustion engine, of a shut-off valve means positioned in the exhaust line of said engine, an air valve in connection with the intake means of said engine for admitting air thereto, a unitary valve control pedal, lever means connected with said control pedal for opening said air valve, and other lever means also connected with said control pedal for closing said shut-off valve after said air valve has been partially opened. 115

4. In an apparatus of the class described, the combination with an internal combustion engine, of a large intake air valve connected with the intake means of said engine where- 120

by the vaporized fuel is reduced to a non-combustible state, and manual means for actuating said air valve.

5. In an apparatus of the class described, the combination with an internal combustion engine, of a valve positioned in the exhaust pipe of said engine, an air intake valve connected with the intake manifold of said engine, a foot pedal means pivotally connected

with said air valve for operating the same, 10 and lever means connected with said foot pedal for shutting off the valve positioned in the exhaust pipe after the air valve has been slightly opened.

In testimony whereof I have hereunto set 15 my hand at San Diego, California, this 14th day of August, 1924.

HARRY H. NOLEN.
